Primary Examiner — Susan Bennett Hattan*Assistant Examiner* — Vy Koenig(74) *Attorney, Agent, or Firm* — Andrus, Sceales, Starke & Sawall, LLP**CLAIM**

The ornamental design for a tablet chair with book rack, as shown and described.

DESCRIPTION

FIG. 1 is an isometric view of a tablet chair with book rack incorporating our new design;

FIG. 2 is a top plan view thereof;

FIG. 3 is a front elevation view thereof;

FIG. 4 is a right side elevation view thereof;

FIG. 5 is a left side elevation view thereof;

FIG. 6 is a rear elevation view thereof; and,

FIG. 7 is an isometric view of the tablet chair with book rack with the tablet rotated to an alternate position.

The portions shown in phantom illustrate environment and form no part of the claimed design.
